WARREN LYON, OF NEW YORK, N. Y.

Letters Patent No. 83,981, dated November 10, 1868.

IMPROVEMENT IN PUNCHING-MACHINES.

The Schedule referred to in these Letters Patent and making part of the same.

To all whom it may concern:

Be it known that I, WARREN LYON, of the city, county, and State of New York, have invented a new and useful Improvement in Punching-Machines, of which the following is a full, clear, and exact description, reference being had to the accompanying drawing, forming part of this specification, and in which—

Figure 1 represents a front elevation of a punching-machine constructed in accordance with my improvement, and

Figure 2, a side view, partly sectional, of the same.

Figure 3 shows an edge view, on an enlarged scale, of the slotted toothed sector, with pitman attached, used to operate the punch-stock.

Similar letters of reference indicate corresponding parts.

This, my invention, consists in a novel arrangement of devices with and for operating a sliding punch or punch-stock, including a lever, pinion, toothed sector, and pitman, eccentrically pivoted at its one end to the latter, and to the punch-stock at its opposite end, whereby a most advantageous application of power is obtained, and by it I am enabled, for a given stroke, to work closer to the centre of the sector, and use a shorter lever than where a cam or eccentric is used to operate the punch-stock.

Referring to the accompanying drawing, A represents the main frame of a hand-punching device, and B the punch-bed or die, over which the metal to be punched is slid from one side along a gauge, C, which should be made adjustable in its attachment to the frame, to suit different kinds or widths of work, that, in thus being guided by the gauge, is also held down to the bed or restrained from lifting with the rise of the punch, by causing the metal to slide under a cap-plate or stop, D, which should likewise be made adjustable in its connection with the frame, and through which, by a slot made therein, the punch, *a*, is permitted to play.

Said punch *a*, that may be of any suitable size or shape, and varied at pleasure, according to the size and character of the hole to be made, is carried by a punch-stock or holder, E, arranged to have sliding motion within and through a box or steadyng-guide, F, secured to the main frame.

This punch-stock E has pivoted or jointed to it, at its top, as at *b*, a pitman, G, which, entering and working within a slot, *s*, made in a toothed sector, H, is eccentrically pivoted thereto, as at *c*, and which, to secure a powerful action, may be at but a short distance or throw from the centre or shaft, *d*, of the sector, said shaft, and also a pinion-shaft, *e*, being carried by suitable projections from the main frame.

The last-mentioned shaft, *e*, carries a pinion or part-pinion, I, which gears with the sector *H*, and is operated by a lever, J, that in being worked from the position shown for it by black lines to that represented for it in red lines, fig. 2, moves the sector *H*, pitman *G*, and punch-stock *E*, to the positions in which said parts are indicated by red lines, or, in other words, completes the downward stroke of the punch *a*.

To give an upward stroke to the punch, the motion of the lever, with its working-attachments, is reversed.

In thus operating my machine, there is great simplicity and steadiness of action obtained, and, as compared with a cam or eccentric to work the punch, it is possible, for a given stroke, to work much closer to the working centre *d*, and to secure a more powerful action of the punch with or through a comparatively short hand-lever, J.

By the slotted construction of the toothed sector *H*, the driving-connection of the latter with the punch-stock, by or through the pitman *G*, is made in direct line with said stock through its centre, which obviates lateral strain, and by which construction bearings, *f*, for the working-shaft, *d*, of the sector, are admissible in all throws or plays of the pitman, however close said pitman may be pivoted to the working-shaft. This gives a steady action or run to the sector.

What is here claimed, and desired to be secured by Letters Patent, is—

The construction and arrangement, hereinbefore described, of the lever *J* and pinion *I*, slotted toothed sector *H*, pitman *G*, punch-stock *E*, guide *F*, and frame *A*, for the purpose set forth.

WARREN LYON.
